(57) **CLAIM**

The ornamental design for a head for portable garment steamer, as shown and described.

DESCRIPTION

FIG. 1 is a perspective view of a head for portable garment steamer showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in FIGS. 2, 3 and 7 are included for the purpose of illustrating portions of the head for portable garment steamer that form no part of the claimed design.

1 Claim, 3 Drawing Sheets
